(57) **CLAIM**

The ornamental design for an optical lens cleaning device, as shown and described.

DESCRIPTION

FIG. 1 is a perspective view of an optical lens cleaning device according to the design in the closed configuration; FIG. 2 is a top view thereof;

FIG. 3 is a bottom view thereof;

FIG. 4 is a right end view thereof;

FIG. 5 is a left end view thereof;

FIG. 6 is a front view thereof;

FIG. 7 is a rear view thereof; and,

FIG. 8 is a top view of an optical lens cleaning device in the open configuration.
